UNITED STATES PATENT OFFICE

PHILIP L. O'DONNELL, OF CINCINNATI, OHIO

AIR SUPPLY SYSTEM

Application filed November 22, 1930. Serial No. 497,617.

This invention relates to an air supply system in which air is supplied to a series of air-using devices from a single conduit.

The invention is particularly contemplated herein in connection with a group of machines utilizing hot air, controllable air supply and air-heating means being associated with each machine, whereby great economy is effected since both the air supply and the heating thereof is made selective with each machine in a series.

An object of the invention is to provide means for supplying a constant volume of air to each machine in the group so that they work with equal efficiency.

Another object is to provide such means which may be installed for use with machines without materially changing the arrangement of such machines.

Another object is to provide a single air supply which efficiency provides for a varying number of air using devices, thus avoiding the expensive of providing individual air supply means for each machine or device.

Another object is to provide such an air supply having means for cutting off the air supply from one or more machines of a group without interfering with the operation of the system as a whole.

These and other objects are attained by the means described herein and set forth in the accompanying drawing, which is a schematic representation of the hot air supply system of the present invention associated with French folding machines.

The chief disadvantage heretofore with regard to groups of apparatus which utilize an air supply from a single conduit, has been that the volume of air as supplied to the later machines in the group was materially less than that supplied to the first and immediately subsequent machines, due to the repeated tappings made upon the single air conduit. This disadvantage has been noted in connection with various kinds of mechanisms and apparatus and particularly with machines such as French folding machines which utilize a blast of hot air for rendering adhesive the tape which such machines are designed to apply.

The system, for the purpose of illustration, is shown in conjunction with French folding machines comprising a base portion 5 and the laterally extending arms 6 and 7, arm 7 being the work-receiving and work-moving member upon which shoe uppers and the like are placed for the purpose of having taping applied to the edges thereof. The upper arm 6 supports the tape folding mechanism, movement of both said mechanisms being supplied through the pulley and belt indicated generally at 8. The operation of French folding machines entails the use of means for rendering sufficiently adhesive the applied portions of the tape. For this purpose a concentrated blast of hot air is directed against such adhesive portions just before the folding operation thereof. The terminal of this hot air supply is shown at the restricted end 9 of the hot air pipe 10 coming from an air heating apparatus indicated generally at 11. Adjacent the machine the hot air pipe 10 may be provided with suitable insulating material 12. The air heating means may be of any suitable type, and as shown herein is of that kind set forth in my co-pending application, Serial Number 363,236, filed May 15, 1929. This means comprises a screen casing 13 within which a hot air cylinder is disposed, said cylinder in turn containing a heating element, these interior elements not being shown herein. The degree of heat of such element may be controlled by the rheostat 14. An end of the hot air pipe 10 communicates with one end of said hot air cylinder and auxiliary air supply pipes 15 and 16, associated with adjacent machines, communicate with the other end of this cylinder, it being understood that the air is heated in its passage through the air cylinder.

Air under pressure is supplied from a suitable air volume moving means indicated at 17 from which the air is passed into a conduit line composed of units of piping, the unit associated with each machine being of a lesser diameter than that of the preceding unit so that the volume of air supplied to the various machines remains constant. It will be seen that the auxiliary supply pipe 15 communicates with a relatively large unit 18, and that

the subsequent pipe unit 19 with which the auxiliary pipe 16 communicates is of relatively less diameter. In similar fashion the pipe unit 20 is of smaller diameter than the pipe unit 19, it being understood that these pipe units are connected by suitable joint means indicated generally at 21.

A cut-off valve 22 of any approved type, may be associated with each auxiliary pipe 15 and 16, for selectively shutting off any one or more of the machines from the air supply, closing of said valve in no way affecting operation of the system as a whole.

It will be seen that by thus diminishing the diameter of the conduit units after supplying the various machines in a given group, that a constant and equal volume of air may be supplied to each for achieving maximum efficiency.

20 What is claimed is:

1. The combination with a series of machines utilizing a hot air supply, of air pressure means, a conduit line communicating therewith, said line composed of units of successively diminished capacity, a take-off conduit communicating with each unit, a plurality of air heating devices associated one each with one of said machines and receiving the air supply from one of said take-off conduits, and a conduit directing the heated air to the associated machine.

2. The combination with a series of air-using machines, of air volume-moving means a conduit line communicating therewith, said line composed of units of successively diminished capacity, a take-off conduit communicating with each unit, a cut-off valve associated with each take-off conduit, a plurality of controllable air heating devices associated one each with one of said machines and receiving the air supply from one of said take-off conduits, and a conduit directing the heated air to the associated machine.

3. The combination with a series of folding machines for applying adhesive tape to shoe uppers, of means for rendering the tape properly adhesive before application thereof and comprising air pressure means, a main conduit line communicating therewith, said line composed of units of successively diminished capacity, a take-off conduit communicating with each of said units, a plurality of air-heating devices associated one each with one of said machines and each receiving the air supply from one of said take-off conduits, a cut-off valve associated with each of the take-off conduits, and a warm-air conduit associated with each air-heating device and having a restricted end terminating adjacent the folding means of the machine and adapted to direct the heated air upon the adhesive portions of the tape immediately before folding of the tape.

4. The combination with a series of folding machines for applying adhesive tape to

shoe uppers, of means for rendering the tape properly adhesive before application thereof and comprising air pressure means, a main conduit line communicating therewith, said line composed of units of successively diminished capacity, a take-off conduit communicating with each of said units, a plurality of air-heating devices associated one each with one of said machines and each receiving the air supply from one of said take-off conduits, a warm-air conduit associated with each air-heating device and having a restricted end terminating adjacent the folding means of the machine and adapted to direct the heated air upon the adhesive portions of the tape immediately before folding of the tape, and means associated with each machine for selectively varying the quantity and the temperature of the air directed upon the tape.

In testimony whereof, I have hereunto subscribed my name this 18th day of November, 1930.

PHILIP L. O'DONNELL.
